DIE ASSEMBLY FOR UTILIZING HYDRO-
STATIC PRESSURE IN A DEEP BODY OF
WATER FOR FORMING SHEETSFrederick C. Hoffman, North Hollywood, Calif.,
assignor to Lockheed Aircraft Corporation,
Burbank, Calif.

Application November 22, 1949, Serial No. 128,836

1 Claim. (Cl. 113—44)

1 This invention has to do with the drawing, forming, pressing and shaping of plates, sheets, and the like, of metal, plastics, and other materials, and has more particular reference to apparatus for performing such operations by means of hydrostatic pressures.

At the present time it is the general practice to employ hydraulic presses having rubber platens, stretch presses, and double action presses to form or shape sheets, panels, etc. Other devices have been introduced, such as the device shown in the patent to L. V. Whistler et al., No. 2,399,775, wherein hydraulic fluid under substantial pressure is introduced into a sealed space in the die to act upon the sheet and force it into the die cavity to form the same. When large panels and sheets are to be formed, it is necessary to provide heavy, expensive forming equipment and where hydraulic fluid is utilized as the forming medium powerful pumps must be operated to develop sufficient pressure to shape or form the sheets. Furthermore, in such cases, the dies must have strong, heavy walls to withstand the pressures to which they are subjected. For example, when workpieces of, say, forty feet long and fifteen feet wide are to be formed, the walls of the die proper and of the outer oil retainer would, of necessity, be of tremendous size and thickness to withstand the internal hydraulic pressures or an excessively large press or clamping mechanism would be necessary to contain the internal pressures. Owing to these and other factors the provision of the equipment necessary to form large panels, and the like, involves a great initial expenditure of money and the operation and maintenance of the large costly equipment is a source of substantial expense.

It is a general object of this invention to provide an inexpensive dependable apparatus for forming, shaping and embossing sheets, panels, plates, and the like, which does not require the installation and operation of large costly forming equipment or the provision and operation of pumps for developing high fluid pressures.

Another object of the invention is to provide apparatus of the character mentioned which utilizes the hydrostatic pressures existing in the sea, lakes, deep wells, abandoned water-filled mine shafts, etc. as the force for shaping and forming the panels, plates, or sheets. In accordance with the invention the hydrostatic pressures existing at selected depths in the sea, deep lakes, etc. may act directly upon the sheets or panels to form and shape them into conformance with the die surfaces or configurations.

2 Another object of the invention is to provide apparatus of the class referred to that may be employed in the forming and shaping of sheets, plates, and assembled panels of practically any size. Because the hydrostatic pressures in the sea, deep lakes, shafts, etc. are very great at substantial depths and are substantially uniform throughout any given depth strata, it is possible to form extremely large panels, and the like, and to shape plates of considerable thickness. The utilization of these high hydrostatic pressures does not, of course, necessitate the provision or operation of pressure developing pumps and may be accomplished by means of relatively simple hoisting means, draw works, or the like.

20 Another object of the invention is to provide apparatus of the character described, wherein the dies and associated parts need not be provided with heavy walls or reinforcements to withstand the sheet forming pressures. In accordance with the invention, the die and associated parts are submerged in the liquid to be subjected throughout their exposed surfaces to like or identical hydrostatic pressures so that it is unnecessary to construct them with heavy pressure 25 resistant walls.

25 Another object of the invention is to provide apparatus of this class in which two or more die assemblies are associated with the lowering or hoisting lines in such a way as to counterbalance one another, thereby reducing the power required to raise the dies from the ocean, lake, or shaft. In one form of the invention one or more die assemblies are secured to each end of a line or cable so that the weight of the die or dies at one end of the cable counterbalances the weight of the die or dies at the other end of the cable to reduce the hoisting power to a minimum. In this arrangement one die assembly is raised to the surface to permit the removal of the shaped sheet or panel therefrom at the same time that the other die is being submerged and lowered through the water to form its contained sheet or panel, thereby markedly reducing the time required for the successive forming operations. In another embodiment of the invention, a series of dies is being lowered through the water while another series of dies is being successively raised to the surface, providing a substantially continuous multiple forming sequence or operation.

30 A still further object of the invention is to provide a practical, effective submersible hydrostatic die assembly wherein the workpiece is securely anchored at its margins and is adequately protected and wherein means is provided

for exhausting or permitting displacement of the air trapped behind the workpiece in the die cavity so as to not interfere with the forming operation.

Other objectives and features will become apparent from the following detailed description of typical preferred forms of the invention throughout which description reference is made to the accompanying drawings wherein:

Figure 1 is a side elevation of one form of the equipment of the invention showing a die in the process of being lowered into the sea or lake;

Figure 1A is a fragmentary plan view of a portion of the apparatus illustrated in Figure 1 showing the hoisting drum and associated parts;

Figure 2 is a fragmentary side elevation similar to Figure 1 illustrating another embodiment of the invention wherein one die assembly serves to counterbalance another die assembly;

Figure 3 is a view similar to Figure 2 illustrating still another form of the apparatus of the invention;

Figure 4 is an enlarged fragmentary perspective view illustrating one of the connections between the line and die of the equipment shown in Figure 3;

Figure 5 is an enlarged transverse detailed sectional view of a die assembly of the character illustrated in Figure 1 showing the sheet or workpiece in full lines in the unformed condition;

Figure 6 is an enlarged fragmentary transverse detailed sectional view of another form of die assembly of the invention showing the workpiece or plate in the stretched and formed condition; and

Figure 7 is an enlarged longitudinal sectional view of the air pressure relief valve incorporated in the die assembly shown in Figure 6.

The method of the invention broadly considered, may be said to comprise generally the provision of a die having a die cavity, the securing of a sheet, plate, panel, or other workpiece in the form of an assembly or one piece part on the die to extend across the mouth of the die cavity, the lowering of the assembly to a selected depth in a body of water, such as the ocean, a lake, or deep shaft, to subject the workpiece to the hydrostatic pressure at said depth to form the workpiece to the cavity and then raising the assembly to permit removal of the formed workpiece from the die. In the following detailed description I will describe several forms of the apparatus of the invention and will describe the method as practiced in utilizing the apparatus, it being understood that various forms of equipment or apparatus may be employed in performing the method.

The apparatus of the invention as illustrated in Figures 1, 1A and 5, may be said to comprise generally a support at the surface of the body of water, which support may take the form of a float or vessel 10, a die assembly 11, having a die cavity 12 across which a workpiece 13 is secured, and a hoisting means 14 and line 15 for lowering the die assembly 11 into the body of water to subject the workpiece 13 to the forming hydrostatic pressure of the body of water and for thereafter withdrawing the die assembly to the surface.

The support mentioned above may be varied in the different situations where the apparatus is to be used. For example, where a deep shaft in the ground containing a column of water is to be utilized as the source of hydrostatic pressure, the support may be in the nature of a

platform, or the like, mounted on the earth's surface at the mouth of the shaft. In other instances, where a deep relatively still body of water is to be utilized as the source of hydrostatic pressure, the support may be in the nature of a platform, or the like, mounted on the earth's surface at the mouth of the shaft. In other instances, where a deep relatively still body of water is to be utilized as the source of hydrostatic pressure, the support may be in the form of a barge, float, pontoon, or the like. Such a barge, raft, float or pontoon may, of course, be employed as the support where the operations are to be carried on at sea. Accordingly, the invention is not to be construed as limited to the use of a ship or vessel 10, as illustrated. The vessel 10 is employed to support and carry the hoisting means 14, the derrick means 16 employed to handle the die assemblies and other equipment, and forms a carrier for the necessary powerplants, auxiliary equipment, etc. as well as serving as a convenient work platform for the workmen. The vessel 10 may or may not be self-propelled. I have shown a self-propelled vessel 10 having a propeller 17 and rudder 18 so that the vessel may be sailed to and from the shore or dock and the desired area of deep water. With the vessel at the selected deep water region it may be anchored in position and I have shown an anchor chain 19 extending from the bow.

The vessel 10 may be constructed to facilitate the lowering and raising of the die assembly 11 and the handling of the die equipment when the worksheets or pieces 13 are installed for forming and are to be removed after being formed. The particular vessel 10 illustrated, has a vertical shaft or well 20 located substantially amidships through which the die assembly 11 and line 15 may be raised and lowered, it being apparent that outrigger or outboard supports may be supplied for this purpose, if desired. A platform 21 is provided on the ship deck, adjacent the shaft 20, upon which the die assemblies 11 may be placed prior to and after forming operations. The derrick means 16, mentioned above, is located adjacent the platform 21 and has a line 22 carrying a hoisting hook 23 and operating over a pivoted boom 24. The derrick means 16 includes an appropriate power source or engine 25 for operating the line 22 and boom 24.

The die assemblies 11 may, of course, take different forms and may be varied considerably in construction without departing from the invention. It is a feature of the present invention that the dies may be large to handle large sheets, panels, and plates that would require the provision of exceedingly large, heavy, costly forming presses, or the like, of the conventional type. In Figure 1, I have shown a die assembly 11 of the form shown in detail in Figure 5, it being understood that the die assembly of Figure 6 or other forms of die assemblies may be used with the apparatus of Figure 1.

The die assembly 11 includes a die body 26 which may be a generally rectangular block-like part and which is provided at one side with the above mentioned die cavity 12. The die cavity 12 may, of course, be of practically any configuration. The panel, sheet, plate, or other workpiece 13, to be drawn or formed, is arranged against the face of the die body 26 to extend across the mouth of the cavity 12. A continuous groove 27 is formed in the face of the die body 26 to contain a sealing ring 28 for sealing with the underface of the workpiece 13 around the

cavity 12 to prevent the entrance of the water into the die cavity. The sealing ring 28 may be of the O ring type, that is it may be a continuous ring of rubber or synthetic rubber of cylindrical transverse cross section. A protective and sealing sheet 29 of rubber, rubber composition, or synthetic rubber, may be arranged across the outer face of the workpiece 13 to entirely cover the same. The sealing sheet 29 is not essential in all applications of the invention but serves to protect the workpiece 13 against contact by the sea or lake water.

A draw or clamp plate 30 is engaged against the outer side of the sheet 29 or when the sheet 29 is omitted the clamp plate 30 is arranged against the outer side of the workpiece 13. The clamp plate 30 is tightly clamped toward the die body 26 to secure the marginal portions of the workpiece 13 in the die assembly. In the simple case illustrated, aligned lugs 31 are provided on the die body 26 and plate 30 and bolts 32 are arranged through openings in the lugs to clamp the plate 30 toward the body and thus secure the margins of the workpiece 13 in the die. The draw plate, or clamp plate 30, may be in the form of a ring to leave the major area of the workpiece 13 and/or its sealing sheet 29, exposed. However, I have shown the plate 30 provided with an apron or skirt 34 extending inwardly to a central opening 33. The under side of the skirt 34 is relieved or concave to leave a pressure chamber 35. This chamber 35 is at least as large in area as the die cavity 12 and its margins follow the marginal contour of the die cavity 12 so that the pressure in the chamber may act on the full area of the workpiece 13 that is to be pressed into the die cavity. The opening 33, which is of substantial capacity, admits the water to the chamber 35 and permits the hydrostatic pressure to act fully upon the workpiece 13 to form the same. The perforate skirt 34 protects the workpiece 13 against injury when the die assembly 11 is being lowered into the sea, raised to the vessel 10, etc.

A ring 36, or the equivalent, is provided on an end of the die body 26 and the above mentioned line 15, which is preferably in the form of a cable, is secured to the ring to carry the die assembly 11. In the embodiment of the invention being described, provision is made to maintain the interior of the die cavity 12 at atmospheric pressure so that air is not trapped and compressed in the cavity during the forming of the workpiece 13. A port 37 is provided in the die body 26 to communicate with the inner portion of the die cavity 12 and a hose 38 is secured to the body 26 to have one end communicate with the port. The air hose 38 has its other end in communication with the atmosphere to allow the free displacement of air from the cavity 12 during the forming of the workpiece. As shown in Figure 1 of the drawings, the hose 38 and the line 15 pass through the well or shaft 20 to the hoisting mechanism 14. The hose 38 may be formed of rubber, or synthetic rubber, and is preferably shielded with wire braid, or the like.

The hoisting equipment or means 14 is provided to lower the die assembly 11 into the sea or lake to the depth required for the hydrostatic pressure forming of the workpiece 13 and to then raise the die assembly to the vessel 10. In accordance with the broader aspects of the invention any appropriate or available means may be utilized to raise and lower the die assembly 11. In Figures 1 and 1A, I have illustrated in a

more or less diagrammatic manner, a draw-works or hoisting mechanism 14 including an engine or power plant 40 driving a sprocket 41 which, in turn, drives a chain 42. The chain 42 operates over a sprocket 43 secured on the shaft of a winding drum 44. The drum 44 is appropriately mounted on the deck of the vessel 10 and has an intermediate flange 45 dividing its active spool into two parts 46 and 47. The cable 15 is wound on the drum part 46 while the air hose 38 is wound on the part 47. A direction changing pulley 48 is mounted on the vessel 10 at the mouth of the well or shaft 20 and the line 15 and hose 38 extend from the drum 44 to pass over the pulley 48 into the shaft 20 so that upon operation of the drum the die assembly 11 may be raised or lowered through the shaft.

In employing the apparatus of Figures 1, 1A and 5, in carrying out the method of the invention, the vessel 10 is anchored or otherwise secured at a point where the ocean or lake is of sufficient depth to provide adequate hydrostatic pressures for the shaping or forming of the given or particular workpieces 13. The material of which the workpiece 13 is formed, the thickness of the workpiece, the size and shape of the die cavity 12 to which the workpiece is to be formed, and other factors, determine the hydrostatic pressure that will be required to shape or form the work. For example, at a depth of 3000 ft. the hydrostatic pressure is approximately 1,290 p. s. i., the hydrostatic pressure in pounds per square inch being substantially equal to the depth in feet multiplied by .43. The workpiece 13 is secured in the die assembly 11, as illustrated in Figure 5, and with the die assembly secured to the line 15 the line and die assembly are lowered into the sea by suitable control or operation of the mechanism 14, the air hose 38 being reeled out together with the line 15. It will be apparent that the hoist or derrick means 16 may be utilized to facilitate connection of the die assembly with the cable 15 and the entrance of the die assembly into the well or shaft 20. The mechanism 14 is operated or controlled to reel off the cable 15 and hose 38, the heavy die assembly 11 sinking by gravity. As the die assembly descends the hydrostatic pressure admitted to the outer face of the workpiece 13 by the opening 33 and chamber 35 increases, tending to force the workpiece into the die cavity 12. The hose 38 maintains the interior of the cavity 12 at atmospheric pressure so that a pressure differential exists across the workpiece 13, this differential increasing with the depth of the die assembly 11. The gradually increasing hydrostatic pressure acting inwardly on the workpiece 13 forces or presses the workpiece inwardly to stretch and form it to the configuration of the cavity 12, the marginal portions of the workpiece being confined between the die body 26 and the draw or clamp plate 30. The broken lines in Figure 5 illustrate the position and shape assumed by the formed workpiece 13. When the workpiece 13 has been shaped or formed in this manner at the calculated or previously determined depth in the water, the hoist mechanism 14 is operated to reel in the cable 15 and hose 38 to raise the die assembly 11 to the surface. When the die assembly 11 has been raised through the well or shaft 20 the boom 24 and line 22 may be utilized to hoist it on to the platform 21 where the plate 30 and protective sheet 29 are removed to allow withdrawal of the shaped workpiece 13 from the die body 26. Another workpiece 13 may then be assembled or

secured in the die assembly 11 and the assembly again lowered through the shaft 20 so that the above procedure may be repeated to shape the second workpiece.

From the foregoing it will be seen that the method of the invention as practiced with the apparatus of Figures 1 and 1A, comprises the steps or operations of arranging a workpiece across the mouth of the die cavity of a die, lowering the die into a body of water to a substantial depth to expose the workpiece to the hydrostatic pressure therein which forms the workpiece into configuration with the die cavity, the withdrawal of the die from the body of water and the detachment of the formed workpiece from the die.

Figure 2 illustrates another form of the invention where two die assemblies 50 are operated on a line or cable 51 in such a manner that one die assembly is lowered as the other is raised, thereby reducing the hoisting or lifting power required and markedly increasing the overall speed and efficiency of the forming operations. In this embodiment of the invention the barge, float, or vessel 52 has two spaced vertical wells or shafts 53 and a drum 54 is rotatably mounted on the vessel between the two shafts. A chain and sprocket drive 55 extends between an engine 56 on the vessel and the drum 54 to drive the drum. The line or cable 51, which has one or more turns on the drum 54, has its opposite end portions extending from the drum to pass down through the wells 53. The die assemblies 50 are secured to the ends of the cable 51 and the parts are related so that one die assembly 50 is at the maximum depth in the water when the other assembly 50 is at the deck of the vessel. It will be seen that by properly operating the drum 54 one die assembly 50 is lowered and the other is raised, the weight of the first assembly partially counterbalancing the weight of the second assembly to reduce the power required to operate the drum 54. The derrick means 16 is preferably located on the vessel 10 so as to handle the die assemblies 50 when they are to be raised and lowered through the two shafts 53.

Die assemblies 11, of the type illustrated in Figure 5 of the drawings, may be operated on the line or cable 51 in which case the air hoses 38 associated with the die assemblies are handled by the drum 54 as the assemblies are lowered and raised. However, I have shown die assemblies 50, of the character illustrated in Figures 6 and 7, attached to the line 51. Each of these assemblies 50 includes a die body 60 provided at its active side with a die cavity 61 of the required configuration. The workpiece 62 is arranged across the mouth of the die cavity 61 to have its marginal portions bear on the face of the die body 60. A seal ring 63, similar to the ring 28 described above, is arranged in a groove 64 in the body 60 to seal with the inner side of the workpiece 62. In this construction the margin of the workpiece 62 has a flange 65 provided with an undercut inner surface 66. A clamp ring or draw ring 67 is arranged against the marginal portion of the workpiece 62 and is shaped to conform therewith, having a tapered lip 68 for cooperating with the undercut surface 66. This engagement positively anchors the workpiece 62 at its margin. The clamp ring 67 has a peripheral flange 69 fitting a channel 70 in the die body and lug and bolt connections 71 removably secure the ring to the die body 60. It will be seen that the clamp ring 67 is positively anchored or held against movement toward the center of the die assembly by the engagement of the flange 69 in

the channel 70 and the lip 68 cooperating with the surface 66 positively anchors the margin of the workpiece 62.

If desired, or found necessary, a protective and sealing sheet 71 of rubber, or synthetic rubber, may be arranged across the outer face of the workpiece 62 and the clamp ring 67 to prevent the water from contacting the workpiece. Further, a protective plate 72, of steel or the like, may be arranged across the face of the die assembly. Cap screws 73, or the like, secure the sheet 71 and plate 72 to the clamp ring 67. The plate 72 is bowed or curved outwardly from adjacent the clamp ring 67 to leave a chamber 74 at the outer face of the workpiece 62 and sheet 71 and a rather large central opening 75 is provided in the plate 72 to admit the hydrostatic pressure to the chamber to act upon the workpiece.

The die assemblies 50 may be provided with ports 37 and air hoses 38, such as above described, to permit the free displacement of air from the die cavities 61 during the forming of the workpieces 62. However, in Figure 6, I have shown the die body 60 provided with an internal cavity 76 communicating with the die cavity 61 to receive the air as it is displaced from the chamber 62. The chamber 76 may be cored in the body 60 and it is desirable to have the capacity of the chamber 76 equal to or greater than the capacity of the die cavity 61, so that upon shaping or forming of the workpiece 62 the volume of the air in the die is decreased one-half or less. This prevents the development of any appreciable air pressure behind or under the workpiece 62 as it is being shaped or formed by the external hydrostatic pressure. It is preferred to provide perforated reinforcing webs 77 in the chamber 76 to strengthen the chambered die body 60. A central port 78 joins the inner wall of the die cavity 61 and connects with lateral ports 79 in the die body 60 to maintain communication between the die cavity and the chamber 76.

Valve means is provided on the die assemblies 50 to allow the escape of air under pressure from the chambers 76 as the die assemblies are elevated to the surface of the water. As shown in Figures 6 and 7, the body 60 of each die assembly 50 has a port 80 leading from the chamber 76 and equipped with an airpressure relief valve. The valve may be in the form of a spring loaded check valve including a tubular body 81 having an outwardly facing internal valve seat 82. A ball 83 is yieldingly urged against the seat 82 by a spring 84. When the die assembly 50 is being raised to the surface of the water the air pressure in the chamber 76 may exceed the external hydrostatic pressure, especially as the die approaches the surface of the water. At this time the air pressure unseats the ball 83 and air is allowed to escape from the die assembly 50. The ball 83, cooperating with the seat 82 of course serves to prevent the entrance of the water under pressure into the chamber 76.

It is believed that the manner of performing the method of the invention with the apparatus of Figures 2, 6 and 7 will be readily apparent from the foregoing detailed description of the apparatus. Assuming that a workpiece 62 is secured in the die assembly 50, illustrated at a depth in the sea at the right side of Figure 2, and that a formed workpiece 62 is to be removed from the die assembly 50 at the left side of the figure, the drum 54 is operated to raise the latter assembly as high as possible to permit it to be engaged by the derrick means 16. The drum 54 is locked and

the line 51 is secured whereupon the assembly 50, at the left, is raised onto the platform 21 so that its workpiece 62 may be removed. A new workpiece 62 is then installed in the die assembly 50 and the assembly is lowered through the left shaft 53 into the sea. The drum 54 is operated to lower the left die assembly 50 and to raise the right assembly 50. As the left die assembly 50 is lowered the hydrostatic pressure increases and acts upon the workpiece 62 through the opening 75 and chamber 74 to press and form the workpiece to the wall of the die cavity 61. Air from the cavity 61 is displaced into the chamber 76 as described above. When the left die assembly 50 reaches the maximum depth the right die assembly reaches the right shaft 53 where it is accessible for engagement by the derrick means 16. The drum 54 and line 51 are locked and the right assembly 50 is opened to remove its formed workpiece 62. It will be observed that the die assemblies 50 counter-balance one another during the raising and lowering operation so that a minimum of power is required. The foregoing operations may be repeated to successively or alternately raise and lower the two die assemblies 50 to form or shape the workpieces 62 by the hydrostatic pressures existing in the sea or deep lake.

Figures 3 and 4 illustrate still another form of hydrostatic pressure forming apparatus wherein a plurality of die assemblies 50 is secured to a continuous line or cable system 86. In this type of apparatus the vessel 52 may be substantially the same as in the form of the invention shown in Figure 2, being provided with the two spaced vertical shafts 53. A large diametered drum 87 is mounted between the two shafts 53 and a suitable engine 88 drives the drum through a speed reduction gearing and drive system 89. The cable system 86, which operates over the drum 87, includes two spaced parallel cables provided with sets or pairs of horizontally aligned clamps 90. Figure 4 of the drawings illustrates one of the clamps 90 in detail. Trunnions 91 project from the opposite sides of the die bodies 60 and are rotatably received in bosses 92 on the adjacent clamps 90. Removable nuts 93 are threaded on the trunnions 91 to prevent disengagement of the trunnions from the clamp bosses 92. Spacers 94 are arranged on the trunnions 91 to hold the clamps 90 spaced away from the die assemblies 50. There may be any desired or required number of spaced pairs of clamps 90 provided on the cables 86 to carry the die assemblies 50. The die assemblies 50 are supported by the trunnions 91 and clamps 90 to hang between the two cables 86.

In operating the apparatus of Figures 3 and 4 to form the workpieces 62 by the method of the invention, the shaped or formed workpieces are removed from the die assemblies 50 as the assemblies successively reach the vessel 52 and the new or unformed workpieces 62 are assembled or secured in the die structures positioned to enter the ocean. By intermittently rotating the drum 87 in one direction the die assemblies 50 are successively brought to the vessel 52 for the removal of the formed workpieces 62 and for the insertion

of the new workpieces. The intermittent advancement of the drum 87 also successively lowers the die assemblies 50 to the maximum depth for the full shaping or forming of the workpieces 62 to the configuration of the die cavities 61 by the hydrostatic pressures of the ocean or lake. With the apparatus of Figures 3 and 4, it is possible to maintain a production line operation wherein a number of parts of the same shape, size, etc. or of different shapes and sizes, are drawn or formed. Thus a minimum of equipment is required in the economical forming of a large number of parts. As illustrated in Figure 3, the derrick means 16 may be utilized to facilitate the handling of the die assemblies 50 at the vessel 52.

Having described only typical forms of the invention I do not wish to be limited to the specific details herein set forth, but wish to reserve to myself any variations or modifications that may appear to those skilled in the art or fall within the scope of the following claim.

I claim:

25 A die assembly for utilizing the hydrostatic pressures in a deep body of water for forming sheets, plates, and like workpieces, comprising, a die body having a die face, an external die cavity formed in said face shaped to conform to the shape desired to be produced on a workpiece, 30 means for securing the marginal portions of the workpiece to the die face with the workpiece extending across the mouth of the external die cavity and closing the same, said die face having a sealing groove, a sealing ring arranged in said groove to seal the inner side of said workpiece, 35 said die body having an internal cavity communicating with said external die cavity to receive air as it is displaced from said external die cavity, said die body having a port communicating with 40 said internal cavity, a tubular insert mounted in said port having an internal valve seat, and a ball valve yieldably urged against said valve seat in the direction of said internal cavity so as to permit air under predetermined pressure to exhaust 45 from said internal cavity without allowing the water to enter therein.

FREDERICK C. HOFFMAN.
